(57) **CLAIM**

The ornamental design for a display screen with animated graphical user interface, as shown and described.

DESCRIPTION

FIG 1 is a front view of a display screen with animated graphical user interface, showing a first embodiment of my new design;

FIG. 2 is a second view thereof;

FIG. 3 is a third view thereof;

FIG. 4 is a fourth view thereof;

FIG. 5 is a fifth view thereof; and

FIG. 6 is a sixth view thereof.

FIG. 7 is a front view of a display screen with animated graphical user interface, showing a second embodiment of my new design;

FIG. 8 is a second view thereof;

FIG. 9 is a third view thereof;

FIG. 10 is a fourth view thereof;

FIG. 11 is a fifth view thereof; and,

FIG. 12 is a sixth view thereof.

The appearance of the transitional image sequentially transitions between the images shown in FIGS. 1-6 and FIGS. 7-12, respectively. The process or period in which one image transitions to another image forms no part of the claimed design.
